UNITED STATES PATENT OFFICE.

WILLIAM W. BATCHELOR, OF CHELSEA, MASSACHUSETTS.

CONVEYER-BELT.

1,079,157.

Specification of Letters Patent.

Patented Nov. 18, 1913.

Application filed August 12, 1912. Serial No. 714,558.

To all whom it may concern:

Be it known that I, WILLIAM W. BATCHELOR, of Chelsea, in the county of Suffolk and State of Massachusetts, have invented certain new and useful Improvements in Conveyer-Belts, of which the following is a specification.

This invention relates to an improvement in conveyer belts.

10 The object of the invention is to provide a conveyer belt, made of canvas or similar material, which is adapted primarily for use on harvesting machinery, and which has advantages over those heretofore in use. As 15 ordinarily constructed, belts of this type are provided at their ends with leather straps and buckles by which the ends are fastened together. These straps are a considerable item of expense, and they cause annoyance 20 and clogging of the machine.

Accordingly, this invention contemplates the provision of a belt which is woven endless and is of the required dimensions, and which obviates the necessity of straps.

25 I will describe my invention in the following specification and point out the novel features thereof in the appended claims.

The invention will be readily understood from an inspection of the accompanying 30 drawing, in which—

Figure 1 is a perspective view of a portion of a woven tube of belting, Fig. 2 is a fragmentary plan view of the belt on an enlarged scale, and Fig. 3 is a sectional side 35 elevation of the belt on a reduced scale.

As illustrated in the drawing, the belting is woven in the form of a tube 10 of indefinite length, which may be provided at intervals with colored or otherwise distinguished thread 12, to indicate where the tubing is to be cut to produce a belt of the desired width. This tubing is of canvas woven in a well known manner, and the circumferential dimension of the tube is equal 45 to the length of the belt required. The tube 10 is cut into the required length along the lines 12, then the edges are turned over to form hems 14, 16. These hems are secured by a zig-zag line of sewing 18, there- 50 by producing pockets 20, which are oppositely disposed and adapted to receive the ends of wooden slats 22. If desired, these

pockets may be woven in the fabric. The slats 22 are affixed to the fabric of the belt by means of rivets 24, or in any other desired manner.

From the construction above set forth it will be noted that the use of straps is entirely obviated, with the consequent noise of the flapping ends when the machine is in 60 operation and tendency to clog the conveyer; the belt is entirely uniform throughout its entire length; and the parts are subjected to even wear.

Changes in atmospheric conditions are 65 readily taken care of with the belt constructed according to this invention, and a uniform product is always obtained.

While I have illustrated and described a preferred embodiment of the invention, I 70 am aware that many modifications can be readily made therein by any one skilled in the art without departing from the scope of the invention as expressed in the claims. Therefore, I do not wish to be limited to all 75 the details of construction illustrated and described, but

What I claim is:—

1. A canvas conveyer belt having pockets at its side edges constructed from the material of the belt, for the purpose set forth.

2. A canvas conveyer belt having pockets at its side edges constructed from the material of the belt, and slats having their ends held in said pockets.

3. A conveyer belt provided with a hem at each edge, each hem being provided with a series of pockets, and slats having their ends held in said pockets.

4. A canvas conveyer belt, having its 90 edges turned over to form hems, and a zig-zag sewing in each hem whereby a series of pockets is formed therein.

5. A cloth conveyer belt having its edges provided with hems, a series of oppositely 95 disposed pockets in said hems, and slats affixed to the belt and having their ends held in said pockets.

In testimony whereof I have affixed my signature, in presence of two witnesses.

WILLIAM W. BATCHELOR.
